FOREIGN PATENT DOCUMENTS

EM 005949864-0002 * 1/2019

Primary Examiner — Paula Allen Greene(74) *Attorney, Agent, or Firm* — Faegre Drinker Biddle & Reath LLP(57) **CLAIM**

The ornamental design for an electronic speaker assembly, as shown and described.

DESCRIPTION

FIG. 1 is a front perspective view of an electronic speaker assembly, illustrating our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawing, the claimed design is defined by the shaded surfaces; the broken lines depict unclaimed environment that forms no part of the claimed design.

1 Claim, 6 Drawing Sheets(56)
